US0D1073658S

(12) **United States Design Patent** (10) **Patent No.:** **US D1,073,658 S**
(45) **Date of Patent:** **** May 6, 2025**

(54) **SUPPORT**

(71) Applicant: **Shenzhen Lanhe Technologies Co., Ltd.**, Shenzhen (CN)

(72) Inventors: **Caili Chen**, Shenzhen (CN); **Dae Young Kim**, Shenzhen (CN); **Bideng Zhang**, Shenzhen (CN)

(73) Assignee: **Shenzhen Lanhe Technologies Co., Ltd.**, Shenzhen (CN)

(**) Term: **15 Years**

(21) Appl. No.: **29/866,836**

(22) Filed: **Sep. 29, 2022**

(30) **Foreign Application Priority Data**

Mar. 31, 2022 (CN) 202230178837.0
Aug. 12, 2022 (CN) 202230528175.5

(51) **LOC (15) Cl.** **14-03**

(52) **U.S. Cl.**

USPC **D14/253**

(58) **Field of Classification Search**

(57) **CLAIM**

The ornamental design for a support as shown and described.

DESCRIPTION

FIG. 1 is a front, right and top perspective view of a support showing our new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

Dash-dash broken lines and unshaded surfaces illustrate portions of the support that form no part of the claimed design. Long dash-short dash broken lines depict boundaries and form no part of the claimed design.

1 Claim, 8 Drawing Sheets
